UNITED STATES PATENT OFFICE.

CHARLES E. EVANS, OF SEATTLE, WASHINGTON.

BINDER TYING AND CUTTING DEVICE.

1,378,169.

Specification of Letters Patent. Patented May 17, 1921.

Original application filed January 11, 1918, Serial No. 211,448. Divided and this application filed August 21, 1919. Serial No. 319,008.

To all whom it may concern:

Be it known that I, CHARLES E. EVANS, a citizen of the United States, residing at Seattle, King county, State of Washington, 5 have invented certain new and useful Improvements in Binder Tying and Cutting Devices, of which the following is a specification.

This application which is a division of my 10 prior application No. 211,448 filed January 11, 1918 and patented December 9, 1919, No. 1,324,239 relates to improvements in binder tying devices and more particularly devices adapted to twist together and cut off the 15 limbs of a binder.

The principal object of the invention is to provide a simple and improved construction which is positive and dependable in action. The various features of novelty and objects 20 of the invention will be apparent from the description taken in connection with the drawings, in which—

Figure 1 is a side elevation of a twister head equipped with a twister constructed in 25 accordance with the present invention, the binder carrier or needle being shown in its uppermost position for delivering the binder to the twisting device;

Fig. 2 is a vertical sectional view through 30 the twister taken on the plane of the binder entering slot;

Fig. 3 is a partial front elevation of the twister head, the binder carrier being removed;

Fig. 4 is a top plan view of the binder cutting device and part of the means for operating the same;

Fig. 5 is a side elevation of the parts shown in Fig. 4;

Fig. 6 is a bottom plan view of the fixed plate at the bottom of the twister device which cooperates with the cutoff disk to hold the binder;

Fig. 7 is a cross sectional elevation 45 through the binder cutoff and holding parts taken substantially on the line 7—7 of Fig. 4; and

Fig. 8 is a top plan view of the housing containing the cutoff wheel.

50 Referring to the drawings which illustrate the at present preferred form of the invention, the binder tying or twisting device comprises a central core 6 having the radial slot 60 adapted to receive the binder 25, the 55 inner portion of said slot being slightly ec-

centric to the axis of the core. This core is mounted to turn freely in a bearing 12' secured to the frame member 12 of the machine, and the bearing has its outer part slotted in a vertical central plane to form an 60 entrance channel for the binder, thus providing two cheeks 13 which preferably are rounded as shown in Fig. 3.

To the upper end of the core 6 is secured a pinion 61 which is formed with a slot 61' 65 corresponding to the slot 60 of the core and is operated by a gear 7 provided with a smooth sector 70 devoid of teeth. The gear 7 also carries a segment bar 71 positioned at a lower level than its teeth. When the parts 70 are at rest, the segment 71 engages one of the concave recesses in a disk 62 which is connected to rotate with the twister core and which also has a slot 63 for the passage of the binder. The gear 7 is coaxial with, and 75 is connected to rotate with, a bevel gear 72, the latter being driven at suitable intervals in any desired manner.

The parts of the binder twister and cutting mechanism are shown separately in 80 Figs. 4, 5, 6 and 7, and assembled in Figs. 1 and 2. As illustrated a plate 8 is secured to the bottom of the twister head by screws 8' and is formed with the binder receiving slot 80 and a recess 81 in its upper surface, said 85 recess constituting a seat for the lower end of the rotative core 6. This plate holds the core against longitudinal movement in one direction and the flange 6^a holds it against movement in the opposite direction. On its 90 under side, as shown in Fig. 6, this plate is provided with a binder receiving and clamping groove 82 and inserted wear plate 83 of hardened metal in which is formed a part 95 of the groove 82.

The wire cutting wheel 84 is journaled on the bolt 87, the axis of which is at one side of the axis of the twister parts that is, eccentric thereto. The wheel 84 has a series of recesses extending inwardly from its periphery forming the teeth 84', the lower corners of the sides of which form cutting members which coact with the edge 58^b of the bottom of the casing 58^a, which may be of hardened steel to form a wire cutting shears.

The finger 57^a carried by the gear 101 engages a tooth 84' so that at each revolution of the gear 101, the cutting disk 84 is rotated through a small angle, thus cutting the binder in the slot 80. The gear 101 is 110

equal in size to its driving gear 102, which is secured to the same shaft as the gears 7 and 72, so that gear 101 rotates at the same angular velocity as gear 7.

5 The upper surface of the teeth 84' are formed with radial grooves as shown at 85 in Figs. 4 and 7, whereby the end of the binder remaining after cutting is drawn into the groove 82 and held securely against the 10 strain of passing the binder about the next bundle, this position of the parts being illustrated in Fig. 7. To secure correct stopping and holding of the cutting disk, each of the 15 teeth 84' may be formed with a peripheral notch 88 which is engaged by the pointed spring held bolt 89.

The wire carrier or needle includes the vertical reciprocating rod or shaft 9 and this rod carries a head 91 to which is secured 20 the bar 92 having the bifurcated ends 93 between which are mounted the binder guiding rolls 94. The head 91 is adapted to be reciprocated vertically by any suitable mechanism and is provided with a pin or 25 pins 95 adapted to enter holes in the cheeks 13 to insure proper registration with the twister mechanism.

In the operation of the machine, one end 30 of the binder being held by the twister device, the head 91 moves downwardly, then the bundle moves against the binder and thereafter the head 91 moves upwardly in rear of the bundle to the position illustrated in Fig. 1. When the head 91 reaches its upper 35 position, it trips the rod 68 which controls the operation of bevel gear 72. This gear 72 is rotated and suitable mechanism is provided so that it makes one rotation only and then stops. When the needle carrier 40 head 91 moves to the position illustrated in Fig. 1, it disposes the binder in the grooves 80, 60 and 63 shown in Fig. 2, so that one end of the binder is held by the grip between the cutoff wheel 84 and plate 8 and the other 45 end is disposed in said slots both ends of the binder thus being slightly eccentric to the axis of rotation of the twister. Consequently if the core and associated parts are rotated, the portions of the binder between 50 the bundle and the lower part of the twister devices will be twisted together. Normally the segment 71 on gear 7 by means of its engagement with the plate 62, holds the twister mechanism against rotation, so that the slot 55 60 of the core will be held in registration with the slot formed between the cheeks 13. When the gear 72 and the rotatively connected gear 7 are started, the segment 71 is carried out of engagement with the plate 62, and the teeth of gear 7 are brought into 60 mesh with the teeth of gear 61, thus rotating the core of the twister. The rotation of the core 6 continues until the smooth or cut-away portion 71 of the gear 7 again comes 65 opposite the pinion 61, thus holding the

twister against rotation, the toothless portion of gear 70 being opposite pinion 61, whereby the latter is not driven. The gear 101, however, rotates through a further slight angle, so that the projection 57^a carried by the gear 101 operates the cutting disk 84 to cut or sever the binder, this cutting taking place between the bottom edge of one of the teeth 84' and the edge of the bottom of the casing 58^a shown at 58^b Fig. 75 4. At the same time the end portion of the binder 25 above the wheel 84 is clamped in one of the grooves 85 between the top of the wheel 84 and the bottom of plate 8, this end being disposed in the groove 82. 80

In this manner the binder limbs are twisted together, the binder is severed and an end thereof held by the twister, so that a new length of binder may be disposed around the bundle. 85

Although a specific form of the invention has been described in detail, it is to be understood that it is not thus limited, but includes modifications and changes which come within the scope of the appended 90 claims.

Having thus described the invention what is claimed as new and desired to be secured by Letters Patent is:

1. A twisting and binder cutting mechanism including in combination, a bearing, a rotary core mounted in said bearing formed with a longitudinal radial slot for the binder the inner portion of which is slightly eccentric to the axis of said core, a flange on the 100 core engaging the bearing to prevent axial movement in one direction, a plate secured to the core at one end and engaging an end of said bearing to prevent axial movement in the opposite direction, a casing secured to 105 said plate having a bottom spaced from the plate, a wheel co-operating with an edge of said bottom to cut the binder mounted in said casing for rotation about an axis eccentric to the core axis and a driving gear 110 secured to the core coaxial therewith.

2. A twisting and binder cutter mechanism including in combination, a bearing, a rotary device mounted in said bearing formed with a longitudinal radial slot for 115 the binder, the inner portion of which is slightly eccentric to the axis of said device and a combined binder cutting and gripping wheel mounted at one end of said device for rotation about an axis eccentric to 120 the axis of the device, and co-operating with the device to grip and hold one end of the binder.

3. A twisting and binder cutting mechanism including in combination, a bearing, a 125 rotary core mounted in said bearing formed with a longitudinal radial slot for the binder, the inner portion of which is slightly eccentric to the axis of said core, a binder cutting wheel mounted at one end of said 130

- core for rotation about an axis eccentric to the core axis, a casing for said wheel having a bottom plate spaced from the core, said wheel formed with teeth the lower edges of which coöperate with an edge of said bottom to cut the binder and the upper surfaces thereof coöperating with the core to grip and hold one end of the binder.
4. A bundle binding and tying machine including in combination, a rotary core, a binder carrier movable to and from said core, a bearing for said core supporting the same with its axis at an angle to the path of the carrier, said core formed with a longitudinal radial slot the inner portion of which is slightly eccentric to the axis of the core, said bearing formed with a slot registering with the core slot when the core is in idle position, a casing secured to one end of the core, a binder cutter wheel in said casing 20 rotatable about an axis offset from the core axis, and means including said wheel for gripping one end of the binder.
5. A bundle binding and tying machine including in combination, a rotary core, a binder carrier movable to and from said core, a bearing for said core supporting the same with its axis at an angle to the path of

In testimony whereof I affix my signature.

CHARLES E. EVANS.
